UNITED STATES PATENT OFFICE.

GEORGE P. WIGGINTON, OF KALAMAZOO, MICHIGAN.

TEMPORARY BINDER OR LOOSE-SHEET HOLDER.

1,143,006.

Specification of Letter's Patent. Patented June 15, 1915.

Application filed August 27, 1914. Serial No. 858,969.

To all whom it may concern:

Be it known that I, GEORGE P. WIGGINTON, a citizen of the United States, residing at Kalamazoo, Michigan, have invented certain new and useful Improvements in Temporary Binders or Loose-Sheet Holders, of which the following is a specification.

This invention relates to improvements in temporary binders or loose sheet holders.

10 My improvements relate particularly to the adjusting mechanism.

The main objects of this invention are: First, to provide in a temporary binder or loose sheet holder an improved adjusting mechanism by means of which the binder may be quickly adjusted to permit the insertion or removal of sheets or leaves or to lock the sheets within the binder. Second, to provide a temporary binder or loose sheet holder having these features which is simple and economical in structure and convenient in operation.

Further objects, and objects relating to structural details, will definitely appear 25 from the detailed description to follow.

I accomplish the objects of my invention by the devices and means described in the following specification.

The invention is clearly defined and 30 pointed out in the claims.

A structure which is a preferred embodiment of my invention is clearly illustrated in the accompanying drawing forming a part of this specification, in which:

35 Figure I is a detail longitudinal section of a structure embodying the features of my invention, sheets or leaves being shown in conventional form. Fig. II is a detail rear or outside view of a structure embodying 0 the features of my invention with the covers extended and separated, the outer walls of the covers being omitted. Fig. III is a detail longitudinal section through the adjusting mechanism, taken on a line corresponding to line 3—3 of Fig. I. Fig. IV is a detail longitudinal section taken on a line corresponding to line 4—4 of Fig. I. Fig. V is an enlarged detail section on a line corresponding to line 5—5 of Fig. II. Fig. 0 VI is a detail section showing the stop taken on a line corresponding to line 6—6 of Fig. III.

In the drawing similar reference characters refer to similar parts throughout the several views and the sectional views are

taken looking in the direction of the little arrows at the ends of the section lines.

Referring to the drawing, the covers are designated generally by the numerals 1 and 2. These covers preferably consist of rectangular frames 3 having walls 4 and outer walls 5 secured thereon. The outer walls are, in practice, faced with a suitable binding 6 of cloth or leather.

The binding or clamping bars 7 and 8 are chambered. The clamping bars are secured to the covers by means of the hinge connections 9. Binding strips 10 extend between the clamping bars, the binding strips in the structure illustrated being secured at 11 to one clamping bar and arranged through holes 12 in the faces of the clamping bars and through the inner side of the clamping bar 8 and extended into the cover 1. The ends of the binding strips are connected to a cross bar 13 in the cover 1, which is provided with a finger piece 14 pivoted to the bar at 15 so that it may be swung down or collapsed, as shown by full lines in Fig. V, or swung up as indicated by dotted lines, 80 to be conveniently grasped.

Within the clamping bar 8 is an adjusting and clamping rod 16 which is flattened at one side to provide a clamping cam or eccentric for the binding strips. The rod 85 16 is journaled in the adjusting member 17 having end portions 18 slidably disposed against the plates 19 at each end of the bar, the plates being slotted at 20 to receive the ends of the rod. The end member 18 is provided with the slides 17' traveling in the ways 17''. When the rod is turned to one position it clamps the binding strips against the member 17, see Figs. I and IV, and when turned to another position it releases the same, so as to permit the clamping bars being pulled apart or drawn together by means of the finger piece 14 which retracts the binding strips into the cover. The clamping rod is adjusted to 90 apply stress to the binding strips by means of the pinions 21 coacting with the racks 22 mounted on the inner wall of the clamping bar 8, the adjusting member being moved laterally by turning the clamping bar which 105 is adapted to receive a key, see Fig. III, the key not being shown.

To retain the parts in their adjusted positions the shaft 16 is provided with a stop wheel 23 coacting with a stop pin 24 on the 110

adjusting member, see Fig. VI. By moving the shaft longitudinally the stops are engaged and disengaged, the stops being held yieldingly in engaged position by means of the coiled spring 25 disposed on the shaft 5 between the end member and the pinion 21 at the inner end of the adjusting member. The racks are of sufficient width to permit the longitudinal movement of the clamping shaft without disengaging the pinions therefrom.

I have illustrated and described my present improvements in a simple embodiment without, however, paying particular attention to proportions, the drawing being illustrative. I have not attempted to illustrate or describe various modifications which I contemplate as I believe the disclosure made will enable those skilled in the art to which 15 my invention relates to embody or adapt the same as may be desired. I desire, however, to be understood as claiming my improvements specifically in the form illustrated as well as broadly within the scope of the appended claims.

Having thus described my invention, what I claim as new and desire to secure by Letters Patent, is:

1. In a temporary binder, the combination 30 of the covers, clamping bars carried by said covers, binding strips arranged transversely through said clamping members extending into one of the covers, a cross bar to which said binding strips are connected arranged 35 within a chamber in one of said covers, said chamber having an inner wall provided with a longitudinal slot, a finger piece for said cross bar disposed through said slot, an adjustable member with which said binding strips are adjustably associated disposed in 40 one of said clamping bars, means for securing said binding strips to said adjustable member comprising a clamping cam carried by said adjustable member, a pinion on said 45 cam, and a rack with which said pinion co-acts whereby the binding strips are clamped and the adjustable member adjusted by the turning of the cam.

2. In a temporary binder, the combination 50 of the covers, clamping bars carried by said covers, binding strips arranged transversely through said clamping members extending into one of the covers, a cross bar to which said binding strips are connected arranged within a chamber in 55 one of said covers, said chamber having an inner wall provided with a longitudinal slot, a finger piece for said cross bar disposed through said slot, an adjustable member 60 with which said binding strips are adjustably associated disposed in one of said clamping bars, and means for securing said binding strips to said adjustable member and adjusting said adjustable member for 65 applying stress to said binding strips.

3. In a temporary binder, the combination with the covers, clamping bars carried thereby, binding strips connected to one of the covers and extending transversely through said clamping bars into the other 70 cover, a cross bar for said binding strips arranged within such cover, an adjustable member with which said binding strips are associated for longitudinal adjustment arranged within one of said clamping bars, 75 means for securing said binding strips to said adjustable member carried by said adjustable member, and means for adjusting said member to apply stress to said binding strips.

4. In a temporary binder, the combination of the covers, clamping bars carried by the covers, binding strips extending between the clamping bars and into one of the covers, a cross bar for said binding strips arranged 85 within said cover, an adjustable member with which said binding strips are adjustably associated adjustably mounted on one of said clamping bars, and means for adjustably securing said binding strips to said 90 adjustable member, said binding strips being free for adjustment by said cross bar when said securing means is released.

5. In a temporary binder, the combination of the covers, clamping bars carried 95 by the covers, binding strips extending between the clamping bars and into one of the covers, a cross bar for said binding strips arranged within said cover, and binding strip securing means carried by one of said 100 clamping bars, said binding strips being free for adjustment by said cross bar when said securing means is released.

6. In a temporary binder, the combination of the covers, clamping bars carried thereby, binding strips extending between said 105 clamping bars into one of the covers, an adjustable member with which said binding strips are associated for longitudinal adjustment arranged within one of said clamping 110 bars, means for securing said binding strips to said adjustable member carried by said adjustable member, and means for adjusting said adjustable member to apply stress to said binding strips.

7. A temporary binder comprising clamping bars, binding strips extending between said clamping bars, binding strip clamping means disposed in one of said clamping bars, and means for adjusting said clamping 115 bars laterally of said clamping bars for applying stress to the binding strips, all co-acting for the purpose specified.

8. A temporary binder, comprising clamping bars, a binding strip extending between said clamping bars, an adjustable member with which said binding strip is associated for longitudinal adjustment carried by one of said clamping bars, a binding strip securing means carried by said adjustable mem-

ber, and means for adjusting said adjustable member, all coacting for the purpose specified.

9. A temporary binder comprising clamping bars, a binding strip arranged transversely through said clamping bars, and a binding strip securing and adjusting means comprising an adjustable member with which said binding strip is associated for longitudinal adjustment carried by one of said clamping members for adjustably securing said binding strip to said adjustable member, and means for adjusting said adjustable member to apply stress to the binding strip.

10. A temporary binder comprising clamping bars, a binding strip extending between said clamping bars, an adjustable member with which said binding strip is associated for longitudinal adjustment carried by one of said clamping bars, a binding strip clamp carried by said adjustable member, and a rack and pinion means for adjusting said adjustable member for applying stress to said binding strip.

11. A temporary binder comprising clamping bars, a binding strip extending between said clamping bars, an adjustable member with which said binding strip is associated for longitudinal adjustment carried by one of said clamping bars, a binding strip clamping cam carried by said adjustable member, a pinion rotatable with said cam, a rack coacting with said pinion, and means for actuating said pinion.

12. A temporary binder comprising clamping bars, a binding strip extending between said clamping bars, an adjustable member with which said binding strip is associated for longitudinal adjustment carried by one of said clamping bars, means for securing said binding strip to said adjustable member, and a rack and pinion means for adjusting said adjustable member.

13. A temporary binder comprising clamping bars, binding strips operatively associated with said clamping bars, a binding strip securing and adjusting means com-

prising an adjustable member operatively associated with said clamping bars, and means for adjustably securing said binding strips to said adjustable member and adjusting said member to apply stress to the binding strips, said binding strip being freely adjustable when said securing means is released.

14. A temporary binder comprising clamping bars, a binding strip extending between said clamping bars, a binding strip securing and adjusting means comprising an adjustable member operatively associated with said clamping bars, and means adjustably securing said binding strip to said adjustable member, and adjusting said member to apply stress to said binding strip comprising a clamping cam, a pinion rotatable with said cam, and a rack coacting with said pinion.

15. A temporary binder comprising clamping bars, a binding strip extending between said clamping bars, a binding strip securing and adjusting means comprising an adjustable member operatively associated with said clamping bars, and means adjustably securing said binding strip to said adjustable member, and adjusting said member to apply stress to said binding strip.

16. In a temporary binder, the combination of the covers, clamping bars carried by the covers, binding strips extending between the clamping bars and into one of the covers, binding strip securing means carried by one of the clamping bars, said binding strips being freely movable when said securing means is disengaged, and an adjusting member to which said binding strips are connected mounted within the cover into which said binding strips project.

In witness whereof I have hereunto set my hand and seal in the presence of two witnesses.

GEORGE P. WIGGINTON. [L. S.]
